UNITED STATES PATENT OFFICE

2,452,337

CIRCUIT ARRANGEMENT FOR THE AMPLIFICATION, FREQUENCY-TRANSFORMATION, OR PRODUCTION OF ULTRA HIGH FREQUENCY OSCILLATIONS

Maximiliaan Julius Otto Strutt and Aldert van der Ziel, Eindhoven, Netherlands, assignors to Hartford National Bank and Trust Company, Hartford, Conn., as trustee

Application May 21, 1943, Serial No. 487,978
In the Netherlands August 20, 1941

Section 1, Public Law 690, August 8, 1946
Patent expires August 20, 1961

3 Claims. (Cl. 250—27)

1

This invention relates to a circuit arrangement for amplification, frequency transformation or production of ultra high-frequency oscillations which comprises a discharge tube successively having at least one cathode, two grids and a further electrode, a resonant circuit tuned to the frequency of the oscillations to be transmitted being connected between the cathode and the first grid having a negative potential or cathode potential.

The properties of tubes for amplifying and generating oscillations at ultra-high-frequencies are greatly different from those at lower frequencies. More particularly in amplifying ultra-high frequencies the fact has to be taken into account that a virtual ohmic resistance is set up between the control grid and the cathode, which resistance exerts a strong damping on the input circuit. The presence of this virtual ohmic resistance is mainly due to two causes.

Primarily the comparatively great transit time of the electrons will involve a phase displacement between the alternating control grid voltage and the alternating current passing through the apertures of the control grid, which phase-displacement involves the production of an influence current to the control grid. This influence current has a component which is in phase with the alternating control-grid voltage and may be construed as resulting from a virtual ohmic resistance available between the control grid and the cathode. The reciprocal value of this resistance is called transit-time damping or electron damping.

Secondly the natural inductances of the supply conductors to the various electrodes will exhibit a considerable impedance in regard to the oscillations to be amplified, so that high-frequency voltages are set up across these supply conductors, which voltages give rise to currents passing through the natural tube capacities and being in phase with the alternating control-grid voltage. The damping of the input circuit thus caused may be called lead damping.

At not too high frequencies both the electron damping and the lead damping are about proportional to the square of the frequency of the oscillations to be transmitted. At ultra-high frequencies the input damping resulting from both of these components is usually so strong that the

2

impedance of the resonant circuit inserted in the signal control grid circuit is high relatively to the input resistance of the tube. Therefore, the output impedance of a stage in cascaded circuits is practically solely determined by the input resistance of the next stage, so that the attainable amplification per stage substantially corresponds to the product of mutual conductance and input resistance. In order to obtain sufficient amplification at ultra-high frequencies the attempts have consequently to be directed to as high an input resistance and mutual conductance as possible.

Recently various proposals have been made to reduce the input damping of amplifying tubes. Thus, for instance, the lead damping can be reduced by making use of a tube having two cathode-supply conductors, one of which is inserted in the input circuit, whereas the other is inserted in the output circuit. Another expedient to reduce the lead damping consists in the use of amplifying tubes comprising two push-pull connected amplifying systems whose cathodes are connected by as short a lead as possible.

25 A further improvement of the input damping is possible by taking various measures essentially amounting to back-coupling, for instance by inserting an additional inductance in the screen-grid lead.

30 In many cases, however, these steps do not yield the desired effect, because the dynamic mutual conductance of the discharge tube highly declines at ultra-high frequencies and is usually much lower than the static mutual conductance.

35 The present invention purports to provide a circuit by means of which the input damping of the discharge tube can be highly decreased or even rendered negative and/or by means of which the decrease in dynamic mutual conductance can be materially reduced.

40 According to the invention the second grid in a circuit of the kind referred to has a positive potential, whereas the next electrode has a negative potential, the construction and the voltages 45 of the electrodes being so chosen that the electrons, at least for the greater part, perform an oscillatory movement in the path between the first grid and the electrode next to the second grid and pass several times through the second grid, the frequency of this oscillatory movement

being such that a decrease in input damping and/or an increase of the dynamic mutual conductance is obtained.

In conjunction with the frequency f of the oscillations to be transmitted the feed voltages supplied to the electrodes are preferably so chosen that the time T required by the electrons for covering the path forth and back between two negative electrodes lies between

$$\frac{2n-1}{2f} \text{ and } \frac{n}{f}$$

where n may represent any whole number.

The invention will be more fully explained by reference to the accompanying drawing in which Fig. 1 depicts input damping and conductance curves of a tube which does not utilize the present invention; Fig. 2 discloses a circuit utilizing an hexode and embodying the basic principle of the invention; Fig. 3 shows input damping and conductance curves of a tube embodying the invention; Fig. 4 shows an embodiment of the invention utilizing a tetrode in an amplifier circuit; Fig. 5 shows an embodiment utilizing a tetrode in an oscillator circuit; Fig. 6 shows a modification of the circuit shown in Fig. 5 utilizing an hexode; Fig. 7 shows an embodiment of the invention utilizing a push-pull tube and circuit; and Fig. 8 is a modified form of tube structure that may be used in the circuit of Fig. 7.

In Fig. 1 the curve I represents the variation of the input damping

$$\frac{1}{R}$$

as a function of the frequency f of the oscillations to be transmitted, if the invention is not used. From this curve it appears that with an increase in frequency the input damping initially increases slowly and then in an ever increasing way and that at very high frequencies, after having attained its maximum value, it decreases again comparatively swiftly at A and finally acquires even negative values on the right of point B. The curve II represents the ratio between the dynamic mutual conductance S and the static mutual conductance S_0 as a function of the frequency. It appears that the dynamic mutual conductance swiftly decreases with an increase in frequency. Hence, the decreasing or even negative input damping in the region on the right of frequency A can not be utilized in practice, since the dynamic mutual conductance is too small in this region. Therefore, the frequency range to which the invention is primarily related lies in the rising branch of curve I, for instance between the frequencies designated D and A, which lies in the range of the centimeter and decimeter waves.

The invention is based on the recognition that it is possible to cause a flow of influence current to the signal control grid, which has a component which is in phase-opposition to the control-grid voltage and consequently involves undamping of the input circuit by causing the electronic stream to reverse its direction after it has traversed the signal control grid and bringing it again in the correct phase into the vicinity of the signal control grid. This may be effected by providing that the signal control grid is followed by a positive grid and a negative electrode and by biasing these electrodes in such manner that the electrons pass through the meshes of the positive grid, are reflected by the negative electrode, traverse again

the positive grid and are reflected again by control grid.

In this case the input circuit may be undamped to such a degree that not only the electrons and the lead damping, but also the damping of the circuit itself is compensated so that the resulting damping becomes negative.

Fig. 2 of the drawing, by means of which the principle underlying the invention will be more fully explained, represents a hexode 1 which is connected as an amplifier and comprises a cathode 1, a signal control grid 2, a positive grid 3, a negative grid 4, a positive grid 5 and an anode 6 which last-mentioned electrode also has a positive potential. Between the cathode 1 and the signal control grid 2 is connected a circuit 8 which is tuned to the frequency of the oscillations to be amplified and to which are supplied the oscillations to be amplified, the amplified oscillations being taken from a resonant circuit 10 interposed in the anode circuit. With suitable values of the feed voltages a part of the electrons on the way from the cathode 1 to the anode 6 will be so strongly braked, due to the negative potential of the grid 4, as to reverse their direction. In the proximity of the signal control grid 2 the electrons reverse their direction again by the action of the electric field of the grid 3, whereupon the same phenomenon is repeated in the neighborhood of the grid 4. This is schematically represented by the wave line 8. The time T required by the electrons for covering the path between the grids 4 and 2 forth and back depends on the construction of the tube and in addition on the direct current voltages of the electrodes.

It now appears that the damping or undamping brought about by the discharge tube on the input circuit depends not only on the frequency f but also on the transit time T .

40 In Fig. 3 the input damping

$$\frac{1}{R}$$

45 of the tube as a function of the product fT is represented by the curve III, which holds in the case that in each instance 70% of the electrons approaching the grid 4 are so strongly braked as to reverse their direction. In Fig. 3, moreover, the curve I is plotted on the same scale, which illustrates the relation existing between the damping and the product fT if there are no reciprocating electrons. In this case T is taken equal to double the value of the time required by the electrons for wandering from the grid 2 to the grid 4. Consequently the curve I of Fig. 3 corresponds to the left part of the curve I in Fig. 1, but is plotted on a different scale. From Fig. 3 it appears that a decrease in damping occurs in the cross-hatched regions. These regions appear to lie about the values

$$fT = \frac{2n-1}{2}$$

65 and $fT = n$, where n may be any whole number. From this it follows that a decreased input damping can be obtained by such a choice of the tube construction and of the feed voltages of the various electrodes that T lies between

70

$$\frac{2n-1}{2f} \text{ and } \frac{n}{f}$$

In this way a considerable decrease in input damping can be obtained and in definite regions even a negative damping occurs which may be

used to make up entirely or partly for the individual losses of the input circuit.

However, in a circuit comprising a hexode, as shown in Fig. 2, the dynamic mutual conductance may be affected by the oscillatory movement of the electrons. According to the invention this unfavorable effect on the dynamic mutual conductance can be reduced to a minimum if the moments at which the electrons approach the grid 4 in each instance after a complete oscillation are always in the correct phase relation to the high frequency voltage on the signal control grid 2. This appears to be the case if the transit time of the electrons approximately corresponds to a multiple of the period of the oscillations to be amplified, i. e., if the product fT is a whole number. If this condition is satisfied the dynamic mutual conductance has again the value represented by the curve II in Fig. 1.

Now there is a range of frequencies, in which the dynamic mutual conductance is not much lower than the value indicated by the curve II in Fig. 1 and in which a decreased input damping is obtained at the same time, so that it is possible greatly to reduce the input damping, whilst the dynamic mutual conductance substantially conserves its initial value.

When replacing a hexode by a tetrode, in which the electrode most remote from the cathode and having a negative potential, is used as an output electrode a suitable choice of the biases of the electrodes even permits the obtainment of a dynamic mutual conductance S exceeding the static mutual conductance S_0 which would be obtained with a normal positive voltage on the output electrode. This is clearly illustrated by the curve IV in Fig. 3, in which the course of the ratio S/S_0 is indicated as a function of fT . If $fT=1$, consequently if the time required by the electrons for covering the path between the two negative electrodes forth and back, corresponds to one period of the oscillations to be amplified, a dynamic mutual conductance can be attained which is several times higher than the static mutual conductance.

Fig. 4 shows an embodiment of the invention making use of this principle. This figure represents a tetrode 10 comprising a cathode 11, a signal control grid 12, a positive grid 13 and a negative anode 14, the latter being used as an output electrode. Between the control grid 12 and the cathode 11 is connected a circuit 15 which is tuned to the frequency of the oscillations to be amplified and is provided in form of a coaxial line in such manner that the cathode is connected to the external conductor, whereas the control grid is connected to the internal conductor. The circuit of the anode 14 includes a similar coaxial line 40, the anode being connected to the internal conductor and a source of potential B_2 being connected to the external conductor. The positive grid 13 is connected to the cathode through a condenser 17. The feed voltages supplied by batteries B_1 and B_2 are so chosen that T lies between

$$\frac{2n-1}{2f} \text{ and } \frac{n}{f}$$

if n is so chosen as to be unity then fT lies between 0.5 and 1, thus simultaneously obtaining a high dynamic mutual conductance and a low, or sometimes negative, input damping.

The negative damping, which occurs at definite values of the feed voltages, may also be used for generating ultra-high frequency oscillations and this by proportioning the resonant circuit connected between the control grid and the cathode

in such manner that the damping of this circuit caused by the losses of its own is smaller than the negative damping exerted by the tube on the circuit.

Fig. 5 represents an embodiment thereof, in which a resonant circuit 15 is connected between the signal control grid 12 and the cathode 11 of a tetrode 10, which circuit may, for instance, consist of a coaxial line whose external conductor is connected to the cathode. The sources of direct voltage B_1 and B_2 supply a positive and a negative voltage respectively to the electrodes 13 and 14 which are so chosen that the electrons perform an oscillatory movement between the grid 12 and the electrode 14, as is schematically shown by the line 16, the transit time T having such a value that a maximum undamping of the input circuit 15 occurs. From Fig. 3 it appears that the product fT therefore has to be so chosen that it lies between $\frac{1}{2}$ and 1. If, moreover, care be taken that the damping of the circuit 15 caused by the individual losses at the frequency f is smaller than the negative damping caused by the discharge tube, then oscillations will be generated in the circuit 15, whose frequency is determined by this circuit.

Fig. 6 represents another form of construction of an oscillator according to the invention, in which a greater energy can be taken from the circuit. In this case use is made of a hexode 20 which comprises a cathode 21, a signal control grid 22, a positive screen grid 23, a negative grid 24, a positive screen grid 25 and an output electrode 26, the latter having a positive potential. Between the control grid 22 and the cathode 21 is provided a circuit 15 which is tuned to the frequency of the oscillations to be generated, a similar circuit 27 is interposed in the anode circuit. The voltages of the electrodes 22, 23 and 24 entirely correspond to those of the electrodes 12, 13 and 14 in the circuit shown in Fig. 5 so that oscillations are generated in the circuit 15. Alternating currents having the frequency determined by the circuit 15 will appear in the anode circuit, as a result of which oscillations having this frequency, can be taken from the circuit 27. The part of the hexode 20 which is constituted by the electrodes 25 and 26, acts as an amplifier in regard to the oscillations generated in the remaining part, since the electronic stream is controlled by the grid 22, so that the energy to be taken from the circuit 27 is larger than the energy produced in the circuit 15. In this circuit arrangement the circuits 27 and 15 are preferably coupled solely through the electronic stream, i. e., neither capacitatively nor inductively, in order to avoid undesirable reaction effects. For this reason the cathode is also provided with two supply leads, one of which is inserted in the input circuit, whereas the other is included in the output circuit, thus avoiding coupling of the circuits 15 and 27 through the impedance of the cathode supply lead.

Furthermore, in order to prevent undesirable damping, the electrodes 23, 24 and 25 should be connected in the most suitable way to the cathode in regard to high frequencies, which may be effected in the manner well known to the art by the use of capacitors 33, 34 and 35 as shown in Fig. 6, or which may be effected by means of suitable Lecher systems or coaxial lines.

In order to decrease the lead damping it is also possible to make use of a push-pull circuit. Fig. 7 represents an embodiment thereof, in which use is made of a double hexode system 30, whose two halves have a common cathode 21, and which comprises two signal control grids 22 and 22'

which are symmetrically arranged with respect to the cathode. The auxiliary electrodes 23, 23', 24, 24' and 25, 25' have cathode potential in regard to high frequencies, which may be effected in the manner known to the art by means of capacitors 33, 33', 34, 34', 35 and 35' as shown in Fig. 7. This can be achieved also by uniting in each instance two corresponding electrodes of the two systems, for instance 23 and 23', into one electrode including the two control grids 22 and 22' and by connecting a point of symmetry of this electrode to the cathode through a conductor whose electric length amounts to a whole number of half wave lengths. This position of the electrodes is represented in plan view in Fig. 8. With a suitable choice of the feed voltages an oscillatory movement of the electrons occurs between the electrodes 22, 24 and 22', 24' respectively, which oscillatory movement is such that the tube exerts a negative damping on the input circuit 15. If the natural damping of the circuit 15 is smaller than this negative damping, oscillations will be produced in the circuit 15 as a result of which high frequency voltages are set up at the electrodes 22 and 22'. These voltages are amplified by the tube so that amplified energy can be taken from the output circuit 27.

We claim:

1. A circuit arrangement for the translation of ultra-high-frequency oscillations comprising a discharge tube which successively contains a cathode, a signal control grid, a first positive grid, a negative grid, a second positive grid and an anode, a resonant input circuit tuned to the frequency of the oscillations and connected between said cathode and said control grid, an output load circuit connected to said anode, said control grid having a negative potential or cathode potential, and all grids except the control grid being at cathode potential with respect to radio frequencies, said grids and anode being so constructed and arranged and the direct current voltages applied thereto being so chosen that the electrons, at least for the greater part, perform an oscillatory movement through said first positive grid and within a region defined by said control grid and said negative grid, the electrons passing several times through said first positive grid and the frequency of this oscillatory movement being so related to the operating frequency of the circuit that a decrease in input damping and an increase in dynamic mutual conductance is obtained.

2. A circuit arrangement for the translation of ultra-high-frequency oscillations comprising a discharge tube which successively contains a cathode, a signal control grid, a first positive grid, a negative grid, a second positive grid and an anode, a resonant input circuit tuned to the frequency of the oscillations and connected between said cathode and said control grid, an output load

5 circuit connected to said anode, said control grid having a negative potential or cathode potential, said anode having a positive potential and all grids except the control grid being at cathode potential with respect to radio frequencies, said grids and anode being so constructed and arranged and the direct current voltages applied thereto being so chosen that the electrons, at least for the greater part, perform an oscillatory movement through said first positive grid and within a region defined by said control grid and said negative grid, the electrons passing several times through said first positive grid and the frequency of this oscillatory movement being so related to the operating frequency of the circuit that a decrease in input damping and an increase in dynamic mutual conductance is obtained.

3. A circuit arrangement for the translation of ultra-high-frequency oscillations comprising a discharge tube system comprising a cathode and 20 in the order named, two signal control grids, two first positive grids, two negative grids, two second positive grids, and two anodes, a resonant input circuit tuned to the frequency of the oscillations and coupled to said control grids, an output load circuit interconnecting said anodes, said control grids being at negative potential or 25 at cathode potential, and all grids except the control grids being at cathode potential with respect to radio frequencies, said grids and anodes being so constructed and arranged and the direct current voltages applied thereto being so chosen that cathode electrons, at least for the greater part, perform oscillatory movements through said first positive grids and within the regions defined by the control grids and the said negative grids, the electrons passing several times through the said first positive grids and the frequency of these oscillatory movements being so related to the operating frequency of the circuit that a decrease 35 in input damping and an increase in dynamic mutual conductance is obtained.
